Fig. 4.

Fig. 5.

Fig. 6.

Fig. 7.

Fig. 8.

Fig. 9.

Fig. 10.

FIG. 1 is a front perspective view of the garment hanger, showing our new design;

FIG. 2 is a rear elevational view of the hanger;

FIG. 3 is a front elevational view;

FIG. 4 is a side elevational view;

FIG. 5 is a bottom plan view;

FIG. 6 is a side elevational view;

FIG. 7 is taken along lines 7—7 of FIG. 3;

FIG. 8 is taken along lines 8—8 of FIG. 3;

FIG. 9 is taken along lines 9—9 of FIG. 3; and

FIG. 10 is taken along lines 10—10 of FIG. 3.

The characteristic features of this design reside in the lower curved end portions of the hanger arms merging into the cross bar and the cross bar itself.

We claim:

The ornamental design for the garment hanger, as shown and described.
